COMBINED SCRAPER AND REST FOR A PAINT BRUSH OR THE LIKE

Walter J. Mundy, Canoga Park, Calif.

Application July 15, 1957, Serial No. 46,934

Term of patent 14 years

(Cl. D9—2)

Fig. 1

Figure 1 is a perspective view of a combined scraper and rest for a paint brush or the like embodying my new design;

I claim:

The design for a combined scraper and rest for a paint brush or the like, substantially as shown.
